(57) **CLAIM**

The ornamental design for a base for a joystick controller, as shown and described.

DESCRIPTION

FIG. 1 is a perspective view of the base for a joystick controller showing my new design;

FIG. 2 is a top plan view thereof;

FIG. 3 is a rear elevational view thereof;

FIG. 4 is a front elevational view thereof;

FIG. 5 is a right side elevational view thereof; and,

FIG. 6 is a left side elevational view thereof.

The broken line showing of various features on the base in FIGS. 1-6 and the handle in FIG. 1 is for illustrative purposes only and does not form part of the claimed design. The unshown bottom of the base forms no part of the claimed design.
